UNITED STATES PATENT OFFICE.

FREDRICH WILHELM RICHARD POEKERT, OF PITTSBURGH, PENNSYLVANIA.

RAILROAD MAIL DELIVERING AND RECEIVING DEVICE.

Application filed March 19, 1924. Serial No. 700,239.

To all whom it may concern:

Be it known that I, FREDRICH WILHELM RICHARD POEKERT, a citizen of the United States, residing at Pittsburgh, in the county 5 of Allegheny and State of Pennsylvania, have invented certain new and useful Improvements in Railroad Mail Delivering and Receiving Devices, of which the following is a specification.

10 This invention relates to an automatically acting mail delivering and receiving device for railroad cars, the invention having for an object the provision of a novel device of this sort in which the arms on the car, on 15 which the mail to be delivered and received, are adapted to be swung automatically through the car door opening to receiving and delivering position, a further object relating to the provision of a novel device on 20 which the mail to be put on the train is placed.

For further comprehension of the invention, and of the objects and advantages thereof, reference will be had to the following description and accompanying drawing, and to the appended claims in which the various novel features of the invention are more particularly set forth.

Figure 1 of the drawing is a side elevational view showing the automatic arm swinging device on the railroad car.

Figure 2 is the plan view of the device on which the mail to be delivered to the car is placed.

35 Figure 3 is a vertical sectional view taken on the line 3—3 of Figure 2.

Figure 4 is a fragmentary transverse sectional view taken on the line 4—4 of Figure 1.

40 Fig. 5 is a fragmentary perspective view of the device that receives the mail bag from the train.

Referring now to Figures 2 and 3 of the drawing in which I have shown the device from which the mail is delivered to the train, the same comprises a structure consisting of a frame 10 in the top of which is formed a delivery platform comprising a series of rollers 11 which are arranged with 45 their axes transverse to the track and on which the bag or bags containing the mail rests. A mail bag is shown at 12 on the platform and has attached thereto, as by the cord 13, a ring 14. In front of these rollers, 50 that is toward the railroad track, I provide a device which removably supports the said

ring, or rings when a number of bags are placed on the platform, in position to be engaged by the element on the mail car. This device comprises a wire coil 16 having its coils relatively closely spaced so that the rings 14 can be frictionally fitted therebetween, this coil extending along the track and being mounted on a flat bar 17 fixed to the frame 10. To receive the mail from the train, a rod 18 is fixed at one end to an upward extension 19 from one side of the frame 10 and extends under and parallel to the coil 16.

For receiving and delivering the mail 70 bags I mount in the mail car, adjacent the sides of the door opening 20 a pair of posts 26 which are arranged for partial rotary movement, these posts having fixed to their lower ends the vertical shaft extensions 26' 75 which project downward below the car body and have bevel gears 27 fixed on their lower ends. These bevel gears 27 are adapted to be selectively engaged by the respective ones of pairs of bevel gears 28 the respective gears of each pair being fixed on a common sleeve 29, these sleeves being mounted on and having feather connections such as 30 with a shaft 32, the gears 28 thereon being spaced apart from one another a distance greater 80 than the diameters of the gears 17 so that as one gear of each pair is moved into engagement with the adjacent gear 27 the other moves out of engagement, the gears being normally held in neutral position by 85 means of coiled expansion springs 34 which surround the shaft 32 and bear on the opposite ends of the sleeves. The posts 26 have angular arms 35 fixed thereto to receive and deliver the mail.

The shaft 32 extends longitudinally under the car body and is adapted to receive constant rotation as the car moves, and to this end it is connected to one of the car 100 wheels to be driven by the latter. As here shown this connection comprises a spur pinion 37 on the wheel axle 38 meshing with a spur gear 39 on a stub shaft 40 on which is also fixed a bevel pinion 41 meshing with a bevel gear 42 on a short longitudinal shaft 43 which has a drive connection, by means of a chain 44 looped over suitable sprocket 105 wheels, with the shaft 32.

The sleeves 29 are adapted to be moved, to bring the proper ones of the gears 28 into 110 mesh with the gears 27 by means of lever arms 48 fixed at their lower ends on rock

shafts 49 and having forked upper ends, engaging the sleeves in any suitable manner. These shafts 49 have fixed thereto the angularly offset arms 48 which are adapted to be 5 engaged, to shift the levers, by rails 50, 50' of suitable length extending along the track and having cam end 51. The levers 48 are connected together to operate inversely in 10 unison, so as to cause the proper ones of the gears 28 to be brought into operation to swing the arms 35 on the posts inwardly and outwardly in unison. This connection is 15 here effected by means of the arms 53 on the levers which project toward one another, one of these arms having a socket 54 in its end in which the end of the other arm engages.

As will be understood, the respective rails 50 and 50' will be spaced along the track in 20 opposite directions respectively from the mail station and are laterally offset from one another. Fixed to the rock shafts 49 are downwardly and rearwardly extending arms 60, 60' which may have rollers 61 on their lower ends adapted to bear on the respective 25 rails.

It is believed that the manner of operation of my improved device will be readily understood from the above description, it being apparent, that when the rail 50 engages the 30 arm 60 the posts 26 will be swung in one direction, and that when the rail 50' engages the arm 60' the posts will be swung in an opposite direction, so that the mail clerk in the car has only to place the mail on the angular arms 35, which are automatically projected outward through the door, and then later moved inward. It will be understood 35 that these rails 50 and 50' are of such length as to cause the gears 27, 28 to remain in mesh for just sufficient time to swing the arms 35 to the desired distance.

Having thus described my invention what I claim as new and desire to protect by Letters Patent of the United States is as follows:

1. In a mail car, mail delivering and re-

ceiving means comprising a pair of posts arranged at opposite sides of the car door opening, mail holding elements on said posts, and means for swinging said posts in 50 unison to project said elements through the said opening, said means including a constantly driven shaft, gears fixed to said posts, pairs of gears feathered on to said shaft and adapted to selectively engage said 55 first gears, a fixed rail, and a device adapted to engage said rail to move said gears into mesh.

2. In a mail car, mail delivering and receiving means comprising a pair of posts 60 arranged at opposite sides of the car door opening, mail holding elements on said posts, and means for swinging said posts to unison to project said elements through the said opening, said means including a constantly driven shaft, gears fixed to said 65 posts, pairs of gears feathered on to said shaft and adapted to selectively engage said first gears, a fixed rail, and a device adapted to engage said rail to move said gears into 70 mesh, said device comprising a lever engaged at one end with said feathered gears and an arm fixed to said lever in to position to engage said rail.

3. In a mail car, mail delivering and receiving means comprising a pair of posts arranged at opposite sides of the car door opening, mail holding elements on said posts, and means for swinging said posts in unison to project said elements through the 75 said opening, said means including a constantly driven shaft, gears fixed to said posts, pairs of gears feathered on to said shaft and adapted to selectively engage said first gears, a fixed rail, and a device adapted 80 to engage said rail to move said gears into mesh, and said springs holding said feathered gears in neutral positions.

In testimony whereof I have affixed my signature.

FREDRICH WILHELM RICHARD POEKERT.
